UNITED STATES PATENT OFFICE.

HENRY L. ZUCKER, OF EAST ORANGE, NEW JERSEY, ASSIGNOR TO A. P. MUNNING & CO., OF NEW YORK, N. Y., A CORPORATION OF NEW JERSEY.

BUFFING AND POLISHING WHEEL.

1,353,207.

Specification of Letters Patent. Patented Sept. 21, 1920.

Application filed November 22, 1918. Serial No. 263,651.

To all whom it may concern.

Be it known that I, HENRY L. ZUCKER, a citizen of the United States, residing at East Orange, in the county of Essex and State of New Jersey, have invented certain new and useful Improvements in Buffing and Polishing Wheels, of which the following is a specification.

My invention relates to improvements in buffing and polishing wheels.

One object of the invention is to provide a buffing or polishing wheel which is substantially ready for use in the form in which it is sold.

Another object is to provide a wheel of this character, the periphery of which is impregnated or treated with a material which facilitates the application of the final abrasive coating by the workman, and avoids waste of material.

In carrying out my invention, after balancing a buffing wheel of predetermined size by arranging the individual sections in proper relation to each other, and marking them to insure proper reassembly, I true up the surface by a specially constructed tool, rotating the buffing wheel in a specially constructed machine which is arranged to draw off most of the lint. The buffing wheel is then thoroughly impregnated with a material which completely fills the interstices of the fibers and so prepares the periphery as to enable it to take the final polishing material immediately and without waste. The material used is a grease having a high melting point. This impregnation is accomplished preferably by applying the material in liquid form by means of a comb or tool having a number of fine points, over which

the liquid flows into and between the various layers of cloth, which make up the buffing wheel. The periphery of the wheel is composed chiefly of projecting fibers or a nap, which by capillary attraction readily absorb and hold the impregnating compound. The chief function of the liquid is to so prepare the fibers that they shall require only a comparatively light coating of abrasive when used by the workman, although said liquid impregnating material may also have the properties of an abrasive in various degrees. The abrasive is preferably a composition made up of decomposed silica, pulverized flint, stearic acid, mutton tallow and pet-

rolatum. The initial application of the 55 grease causes the fibers to become impregnated as a result of which, when the workman applies the final abrasive, the said abrasive is held to the fibers instead of being thrown off into the exhaust.

In what are known as pieced buffs, it is practically impossible to obtain a perfect balance in the individual sections. In buffs made of full disks of cloth, it is possible to obtain a perfect balance in the individual 60 sections. The completed buff may be sold in the form in which it is finished and used in identically the same form, or the workman may separate the individual sections to make a buff of different thickness for special 65 work. Under these conditions, a composite buff made up of such balanced sections will also be balanced. In cases where irregularities in the individual sections destroy the balance of the individual sections, it is necessary to use the particular sections in the 70 same relation in which they have been assembled originally. To use the buff it is necessary merely to fasten it on the arbor, rotate it, apply the usual coating of polishing 75 material, which has to be applied from time to time in the daily operation in any case, and press the work piece against the periphery.

The buffing and polishing wheel shown in 80 the accompanying drawings will serve to illustrate the improvement described herein.

Figure 1 is a front elevation of a buffing wheel made up of individual sections.

Fig. 2 is a side elevation thereof, and 85

Fig. 3 is a front elevation of an individual section.

The buffing or polishing wheel 1 or "buff," as it is called, consists of a plurality of individual thin buffing wheels 2 or buffing 90 wheel sections. Each section consists of a plurality of layers of cloth which may be complete flat disks or other conventional arrangement of the fabric. The individual cloth layers are preferably stitched together 95 as shown at 3 in Fig. 2. The composite buff 1 is built up of any desired number of such individual sections, which are mounted on an arbor (not shown) and clamped together 100 in any suitable manner. The periphery of each section, and hence of the composite buff, 105 consists of small projecting threads constituting a nap 4. The impregnating material

is absorbed by this nap and the fabric immediately beneath it forming an impregnated outer ring 5.

Since the invention may be embodied in various forms, I do not desire to limit myself to the particular type of buffering wheel disclosed herein except where limitations appear in the appended claims.

I claim:

1. As a new article of manufacture, a buffering wheel section comprising pieces of cloth stitched together and of circular outline, the outer periphery only being impregnated with a substance which facilitates the adhesion of an abrasive.

2. As a new article of manufacture, a buffering wheel comprising layers of fabric held together, having a circular outline and with the peripheral threads forming a nap, the nap only being so impregnated as to require merely a final abrasive coating to render said buffering wheel effective.

In testimony whereof, I have subscribed my name.

HENRY L. ZUCKER.
